UNITED STATES PATENT OFFICE.

ARTHUR O. DADY, OF NEW YORK, N. Y., ASSIGNOR TO PFANSTIEHL COMPANY, INCORPORATED, OF NORTH CHICAGO, ILLINOIS, A CORPORATION OF NEW YORK.

VALVE AND MEANS FOR COOLING THE SAME.

1,306,470.

Specification of Letters Patent. Patented June 10, 1919.

Application filed January 2, 1918. Serial No. 209,891.

To all whom it may concern:

Be it known that I, ARTHUR O. DADY, a citizen of the United States, residing at New York, in the county of New York and 5 State of New York, have invented a certain new and useful Improvement in Valves and Means for Cooling the Same, of which the following is a full, clear, concise, and exact 10 description, reference being had to the accompanying drawings, forming a part of this specification.

This invention relates to valves for internal combustion engines, and is particularly concerned with valves of the so-called 15 mercury cooled type, these valves being provided with hollow heads and stems which contain a small quantity of mercury which when the valve is in operation is vaporized in the head thereof. This vapor is condensed on the walls of the valve stem and 20 returned to the head of the valve, this cycle being repeated over and over whereby the heat is transferred from the valve head and radiated through the wall of the valve stem. 25 Ordinarily the valve stem is of such dimensions that it of itself does not constitute an efficient heat radiating means and means have heretofore been employed for increasing the radiating surfaces of the valve 30 stems, but, so far as I am aware, these means were not carried by the valve stem and were not, therefore, in intimate contact with the outer wall of the valve stem. The result of such a structure is that considerable 35 resistance is offered to the conduction of heat from the valve stem to the radiating means.

The objects of my invention are, therefore, to provide a highly efficient radiator for conducting the heat from the valve stem, 40 said radiator being carried by the valve stem and in intimate contact therewith, and, further, to provide a radiator for the valve stem having a maximum radiating surface but comparatively small weight.

45 Further objects will appear as the description of my invention progresses, reference being had to the accompanying drawings in which,

Figure 1 is a partial central longitudinal 50 section through a hollow valve equipped with my improved radiating means which is shown in elevation;

Fig. 2 is a plan view of one of the corrugated disks which form a radiating element of my improved radiator; and

55 Fig. 3 shows a modified form of the corrugated disk.

Referring to the drawing, the reference character 5 indicates the hollow stem of a valve which comprises a hollow head 6 in communication with said stem. The stem 5 is provided with an extension 7 of reduced diameter on which is tightly fitted a brass or copper sleeve 8 having a shoulder 9 at one end thereof. In order to provide a 60 large radiating surface without materially increasing the weight of the radiator I assemble a plurality of alternate flat and radially corrugated disks 10 and 11 respectively upon the hollow tube, the perforations in 65 these disks being of substantially the same diameter as the diameter of the tube 8 so as to offer but a little resistance to the conduction of heat from the tube to the radiating elements. If desired the inner edges of 70 these disks may be sweated to the tube 8. Another method of securing the radiating elements on the tube is to merely sweat or otherwise secure the end disk 10' to the tube. A pin 12 extending through the end of the 75 tube 8 and the closed end of the valve stem prevents the radiator from being displaced therefrom. A groove 13 formed between the end of the valve stem 5 and the collar 14 is intended to receive the means for actuating 80 the valve. The disks 10 and 11 are preferably formed of copper or aluminum on account of their high heat conductivity, but may be made from other heat conducting 85 materials.

90 In Fig. 3 I have illustrated a modified form of corrugated disk in which the corrugations instead of extending radially, as in Figs. 1 and 2, are parallel to each other.

95 While I have described the preferred embodiment of my invention, it is to be understood that my invention is not limited to the details thereof, but is capable of other modifications within the scope of the appended claims.

100 Having thus described my invention, what I claim as new and desire to secure by Letters Patent of the United States is:

1. A valve having a hollow head and a hollow stem communicating therewith in 105 combination with a tube tightly fitting said

stem, and a plurality of perforated alternate flat and radially corrugated disks assembled on said tube and secured thereon.

2. A valve having a hollow stem in combination with a tube tightly fitting said stem, and a plurality of perforated alternate flat and corrugated disks assembled on said tube and secured thereon.

3. A valve having a hollow stem in combination with a tube tightly fitting said stem, and a plurality of perforated corrugated disks surrounding said tube and in contact therewith.

4. A valve having a hollow stem in combination with a tube tightly fitting said

stem, and a plurality of perforated disks surrounding said tube and continuously contacting therewith.

5. A valve having a hollow stem in combination with a tube tightly fitting said stem, and a plurality of disks surrounding said tube and in contact therewith.

In witness whereof, I hereunto subscribe my name this 21st day of December, A. D. 1917.

ARTHUR O. DADY.
